QUICK RELEASE CLOTHES WRINGER

Filed Aug. 15. 1921

Patented Sept. 2, 1924.

1,507,228

UNITED STATES PATENT OFFICE.

STEPHEN BONA, OF UNION CITY, CONNECTICUT.

QUICK-RELEASE CLOTHES WRINGER.

Application filed August 15, 1921. Serial No. 492,226.

To all whom it may concern:

Be it known that I, STEPHEN BONA, a citizen of the United States, and a resident of Union City, county of New Haven, and 5 State of Connecticut, have invented certain new and useful Improvements in Quick-Release Clothes Wringers, of which the following is a specification.

This invention relates to clothes-wringers, and more particularly to an improved "quick-release" attachment, which will enable the wringer-rolls to be instantly separated whenever desired.

One object of the invention is to produce 15 an attachment of this nature which will be cheap to manufacture, simple, strong, easy to operate, durable, and practically fool-proof in use.

With this and other objects in view, there 20 are illustrated in the accompanying drawings two forms in which the invention may be conveniently embodied in practice.

Fig. 1 represents a front view of a complete wringer, showing the improved attachment in place.

Fig. 2 is a side view of the wringer, partly in section, showing the wringer-rolls in closed position.

Fig. 3 is a view of the wringer, similar 30 to Fig. 2, but with the wringer-rolls in open position, and showing a fabric in place therebetween.

Fig. 4 is a perspective view of the quick-release attachment separated from the 35 wringer.

Fig. 5 is a rear perspective view of one end of a modified form of quick-release attachment.

Referring now to the drawings, in which 40 similar numerals denote corresponding parts throughout the several views, the upper and lower wringer-rolls 1 and 2, which are preferably formed of rubber, are carried by the mandrels or cylinders 3 and 4. The upper roll is pivoted at its ends 5, 5 45 in the two upper roll-bearing arms 6, 6; while the lower roll 2 is similarly pivoted at its ends 7, 7 in the two lower roll-bearing arms 8, 8, as shown in Figs. 2 and 3.

50 The roll-bearing arms 6 and 8, at the left-hand end of the wringer, are pivotally connected together by the short pin 9, as shown in Fig. 1; the roll-bearing arms 6 and 8 at the right-hand end of the wringer 55 are similarly connected by the short pin 10.

The wringer is preferably driven by

hand power and for this purpose the left-hand ends 5 and 7 of the upper and lower rolls are provided with meshing gears 11 and 12 respectively. The gear 12 is directly 60 driven by the driving shaft 13, which is an extension of the left-hand end of the lower roll 7. This shaft 13 has rigidly mounted thereon a crank or handle 14, detachably secured in place by means of 65 the nut 15, screwed upon the end 16 of the shaft 13. As will be evident, this arrangement permits the handle 14 to be readily removed whenever it is desired to substitute power from mechanical sources—in which 70 case the power may be transmitted to the shaft 13 by a pulley, an electric motor, or other suitable mechanism.

The usual drain-board 17 extends the full 75 length of the wringer, and is secured at each end by the ears 18, 18, attached to the tub-clamps 19, 19 by the screws 20, 20. This drainboard 17 is preferably made of malleable iron, but may be constructed of any other suitable material if desired, such as 80 wood, tin, etc.

Each of the tub-clamps 19 is U-shaped, and consists of two vertical legs 20^a and 21, and an intermediate base section 22, the base section being enlarged, and provided 85 with a cylindrical bearing for the vertical roll adjusting shaft or standard 23, as will be hereinafter more fully described. The front vertical leg 20^a of the tub-clamp is also enlarged, and is internally threaded 90 to receive the tub-clamping screw 24, which has the disc-shaped shoe 25 swiveled to its inner end. An adjusting hand-wheel 26 is also provided integral with the tub-clamping screw 24 and located at its outer 95 end. By turning this hand-wheel 26, the shoe 25 may be moved toward or away from the rear vertical leg 21, which is preferably rigid and non-adjustable, and any desired pressure may be thus exerted on the 100 tub.

Each of the standards 23 is firmly anchored upon the intermediate section 22 of the tub-clamp 19 by means of the lock nuts 26^a and 27 on the corresponding side of 105 the wringer, located respectively above and below said intermediate section 22. A washer 28 is preferably located between the lower nut 27 and the intermediate section 22.

Mounted in spaced relation on the shaft 23, immediately above the top lock-nut 26^a,

are the enlarged annular seats of the roll-bearings, the opposite faces of said annular seats being raised slightly from the remainder of the roll-bearings, as shown.

5 The lower roll-bearing face rests firmly upon the top of the nut 26^a; while the face on the upper roll-bearing forms a seat for the lower end of the spiral pressure spring 29, the tension of which may be slowly adjusted by the upper hand-wheel 30, which is preferably knurled, threaded upon the upper end of the standard 23. The pressure from this hand-wheel 30 may be transmitted to the spring 29 through a spring block 31 which has a flanged lower portion provided with a shouldered seat 32 for the upper end of the spring. This arrangement of parts is clearly shown in Fig. 3, where it will be evident that if the hand-wheel 30 is screwed downwardly on the shaft 23, the tension of the spring 29—and consequently the pressure between the wringer-rolls—will be slowly increased. A slow release of the pressure on the rolls 25 may be obtained by reversing the movement of the hand-wheel 30—i. e. by turning it upwardly.

In many cases, however, in order to economize in time and labor it is extremely desirable to quickly release the rolls to permit the passage of a garment having a thick fold, a large button, or the like. To provide for such emergencies, the quick-release attachment now to be described, has been 35 provided.

This quick-release attachment comprises a cross-arm 36 extending from one side of the wringer to the other, and having at each end a pair of downwardly projecting lugs 40 33 and 34. Said lugs 33 and 34 have slots in their lower portions adapted to slide down over pintles 35 formed on the opposite flat faces of the spring-blocks 31. After being thus slid into position, the ends of the lugs 45 are swaged slightly about the pintles to lock them permanently in position. The cross-arm 36 is preferably horizontal near its ends, but is curved upwardly at the center and has its edges rounded so as to afford a 50 smooth grip for the hand of the user.

As clearly illustrated in Fig. 4, the lugs 33 and 34 are connected only at their forward parts, and are open at their rear portions. This construction permits the cross-arm 55 to swing forwardly about its pivots 35, without interference with the adjusting shaft 23.

The upper ends of the lugs 33 and 34 are raised slightly to form cams 37 and 38, which ride upon the hand-wheel 30 when the cross-arm is rocked forward to release the pressure on the rolls. Thus the cross-arm 36 with its associated lugs 33 and 34 60 serves as a trip, which when actuated, suddenly releases the tension of the springs.

The normal or closed position of the rolls is illustrated in Fig. 2, where the cams on the top of the lug 33 of the quick-release device are shown in engagement with the hand-wheel 30. In this position the spring 29 is compressed to its maximum amount and the rolls are tightly pressed together.

When it is desired to instantly release the pressure on the rolls, it is merely necessary to grasp the cross-arm 36 at its center, and pull it forwardly and downwardly to the position shown in Fig. 3. This movement of the cross-arm will trip the spring-blocks 31, and allow them to rise under the pressure of the springs 29 to the open position illustrated in Fig. 3. When in this open position, the rolls may be readily separated, as shown, to permit the clothes to be removed.

When it is desired to again put pressure on the rolls, the hand-wheels 25, at each end 85 of the wringer, are unscrewed sufficiently to permit the lugs on the cross-arm to be easily sprung into the normal closed position; after which the hand-wheels are screwed down again till the rolls are brought 90 to the desired tension.

In the modification illustrated in Fig. 5, a device is shown which will not only quickly release the pressure on the rolls, but will also instantly restore it to its original tension. This device is similar in construction to the quick-release attachment disclosed in Figs. 1-4, but differs therefrom in having rear cam portions 39 and 40 joined to its top cam sections 37 and 38 so as to form continuous cam surfaces from the tops to the bottoms of the lugs 33 and 34. To release the pressure on the rolls of a wringer to which this attachment has been applied, the cross-arm is rocked from the full-line to the dotted position of Fig. 5. To restore the pressure the hand-wheels 25 do not have to be unscrewed, but it is merely necessary to rock the cross-arm back upon its pivot from the dotted (released) position to the full line 105 (closed) position.

While there have been disclosed in this specification, two forms in which this invention may be embodied, it is to be understood that these forms are shown for the purpose 115 of illustration only, and that the invention is not to be limited to these specified disclosures but may be modified or embodied in various other forms without departing from its spirit; in short, the invention includes all the modifications coming within the scope of the following claims.

Having thus fully described the invention, what is claimed as new, and for which it is desired to secure Letters Patent, is:

1. In a clothes-wringer, a frame, a pair of rolls mounted in said frame, a pair of standards connected to said frame, helical springs surrounding said standards for pressing said rolls together, a cross arm ex- 120 125 130

tending between said standards, a pair of lugs on said cross arm, a pair of spring-engaging members surrounding said standards and pivoted to said lugs, said cross-arm being provided with cam surfaces in contact with stationary means on said standards whereby on movement of said cross arm about its pivots in one direction, said springs will be suddenly released, said springs being adapted to be restored to their original condition by moving said cross arm in the opposite direction.

5   2. In a clothes-wringer, a frame, a pair of rolls mounted in said frame, a pair of stand-

ards connected to said frame, helical springs 15 surrounding said standards for pressing said rolls together, a cross arm extending between said standards, a pair of lugs on said cross arm, a pair of spring-engaging members surrounding said standards and pivoted 20 to said lugs, said cross arm being provided with cam surfaces for engaging stationary means on said standards whereby on movement of said cross arm about its pivots, said springs will be suddenly released. 25

In testimony whereof, I have affixed my signature to this specification.

STEPHEN BONA.
